ROLL SPLITTER

BACKGROUND OF THE INVENTION

1. Field Of The Invention

Mechanism for operating upon a roll of paper or stack of sheets of steel or aluminum to split same along a radius thereof without noise, dirt or danger.

2. Description Of The Prior Art

Heretofore, in paper mills, the roll splitting operation has been a manual one, the millhand inserting a picking tool, shaped much like a letter opener, at one side of the roll and underneath such a number of layers of paper as he is capable of tearing with his own strength merely by the procedure of running the picking tool across the top of the roll so as to split such layers longitudinally thereof. Such an operation obviously involves brute force and, even though the millhand may possess unusually great strength and be capable of splitting a large number of layers in one pass, the operation is nonetheless back breaking, time consuming and, of course, costly.

It has heretofore been proposed also to effect the splitting of such rolls by means of the skill saw or the soft-bladed knife method, but such methods have proved to be unsatisfactory in that they are slow and laborious and create problems of paper dust and litter.

Still another proposal has been the guillotine knife type of construction, but same requires extremely high pressures which occasion the need for heavy floor reinforcing. Too, mill headrooms may be such as to preclude use of a guillotine.

SUMMARY OF THE INVENTION

The invention relates to structural refinements in a roll splitter and is directed particularly, but not exclusively, to the provision of a mechanism for operating upon a roll of paper so as to split same along a radius thereof and which substitutes an oscillating cutting blade for the more common cutting action of a guillotine knife to allow a cutting through action without dictating a need for the high pressures common with the guillotine type of knife.

The splitting action is accomplished by a rapid reciprocating motion of the cutting blade, together with a regulated pressure over and beyond the weight of the blade assembly itself so as to effectuate cutting cleanly and quickly through the roll to the center or to the core thereof.

The cutting movement of the blade assembly may be stopped before the blade reaches the core of the roll, thus offering substantial savings through core salvage.

The splitter has a capacity for cutting a paper roll such as a reject roll or an end roll as cut off from the end of a finished roll or reject roll of paper, preparatory to returning the paper so slit to a broke beater or hydropulper wherefore same may be repulped to a slush for reuse in the paper making process. Usually the rolls serviced are large diameter rolls, the paper thereof being substantially continuous, the roll being reduced to a plurality of sheets or strips of limited length.

Substantially constructed of fabricated steel, the roll splitter is relatively light in weight and compact in form so as to be readily installed next to a pulper or transported about at will. Standard models may cut rolls up to 100 inches face and up to 60 inches diameter, with the cutting blade being driven by from a 1 1/2 to a 3 h.p. electric motor, dependent upon the splitter width.

Easily accommodatable to any size of roll, diameterwise and widthwise, the raising and lowering of the knife, and the clamping of the roll, are handled either pneumatically or hydraulically. During cutting, the roll or rolls are held or clamped by a pneumatic arrangement. The operator can stop the splitter before the blade reaches the core. There is a complete absence of dust and litter resulting from the cutting operation.

Broadly speaking, the invention envisions a pair of spaced, parallel, vertically-extending stands, each arranged on a foot 12, and so disposed as to each other that the roll to be split may be located therebetween in a fixed position relative thereto and

beneath a horizontally-disposed and horizontally-reciprocating cutting knife, similar to a guillotine, which knife is supported and guided by the stands. The locating of the cutting knife is controlled by a powered air or hydraulic cylinder which permits the knife to be raised or lowered relative to the roll to be split. The knife is preferably, though not obligatorily, longer in length than the width of the roll to be split.

The cutting knife is set down from a nonoperative position away from to an operative position upon the peripheral surface of the roll to be split by means of the cylinder which vertically adjusts its location. The cylinder provides a sufficient weight to cause the knife to bear heavily upon the roll for the cutting action.

15 The tool which attacks a roll radially and acts not only to sever consecutive layers of the roll but also to separate these along the line of severance so as automatically to provide clearance for the further advance of the tool. These large rolls, when not supported at the sides are quite elastic and subject to 20 considerable deformation before cutting takes place. For this reason, a slow, gradual approach of the tool is preferred to a rapid, impact action.

25 With the equipment motor operational, the knife is rapidly reciprocated in longitudinal directions so as to effect a severing of one layer after another of the paper of the roll through a radius of the roll to the core. As the succeeding layers of paper are cut, the opposite ends thereof, as provided by the cutting action, fall of their own weight and, by the wedging action of the knife, fall away from each side of the knife to form a flat pile on the floor, pallet or conveyor forwardly and rearwardly of and beneath the roll. When the knife reaches the roll core, the cutting action may be terminated, the core removed, and the resulting paper slabs then disposed of, as desired. The pile 30 of sheets so provided may be fed directly into a broke beater or hydropulper, there to be converted into a mass of liquid pulp suitable for reuse in the papermaking process.

35 The extreme pressures normally required for a vertically-disposed knife, in order to produce a capacity for driving the 40 knife downwardly through the successive layers of paper, are not requisite here. That is, the action hereof is likened to that of a saw moving back and forth so that the features of power and strength required in the supporting structure are advantageously less than those found necessary in known prior 45 art apparatus operating on the principle of a knife which is forced vertically downwardly through the mass of paper in the roll being severed.

BRIEF DESCRIPTION OF THE DRAWINGS

50 FIG. 1 is a broken, front elevational view of apparatus embodying a preferred form of the invention;

FIG. 2 is an enlarged top plan view of the power clamp means;

55 FIG. 3 is an enlarged top plan view of the manual clamp means; and

FIG. 4 is an elevational view of the manual clamp means.

DESCRIPTION OF THE PREFERRED EMBODIMENT

60 I have shown a frame comprising a pair of spaced, parallel, vertically-extending stands 10, each arranged on a foot 12, and an upper, horizontally-disposed, transversely extending, cross brace beam 14 fixed to and interconnecting stands 10 at their upper extremities.

Feet 12 may be secured to the floor by any conventional means to impart strength and rigidity thereto and to eliminate objectional vibration or other movement thereof.

65 A roll of paper, not shown, is disposed centrally of and between the stands with the lowermost periphery of the roll being in contact with and supported upwardly of the floor or base. Conceivably, if the roll is of great weight, it may be loaded as by rolling it along the floor to its proper operative position between the stands, or it may be moved thereto as by a lift truck or the like.

The roll is cradled firmly in position relative to the apparatus by a pair of telescopic clamping devices, one of which may be power operated and the other of which may be manually operated. Alternatively, both may be power operated or both may be manually operated.

The power operated clamping device, generally indicated by 20, comprises a horizontally-extending clamping plate 22 fixed to the inner ends of each of a pair of spaced, parallel, horizontally-extending guide rods 24, each of which is slideably related to a guide sleeve 26 fixed in, and extending horizontally outwardly from, a bracket 28 fixed to one of stands 10 by bolts 30 with nuts 32 threadedly engageable therewith.

Air or hydraulic cylinder 34, fixed centrally of bracket 28 as by bolts 36, has a piston rod 38 extendable through the bracket and has its innermost end fixed centrally of clamping plate 22 by a bolt 40, the piston rod being located centrally between and coplanar with guide rods 24.

Actuation of the cylinder moves the piston rod forwardly or rearwardly to move clamping plate 22 toward or away from the end of a roll of paper disposed between the stands, with guide rods 24 sliding relative to guide sleeves 26.

The manually operated clamping device, generally indicated by 50, comprises a horizontally-extending clamping plate 52 fixed to the inner ends of each of a pair of spaced, parallel, horizontally-extending guide rods 54, each of which is slideably related to a guide sleeve 56 fixed in, and extending horizontally outwardly from, a bracket 58 fixed to one of stands 10 by bolts 60.

Extensions 70, telescopically related to each clamping device, accommodate short rolls and comprise a supplemental clamping plate 72 fixed to the inner ends of each of a pair of spaced, parallel, horizontally-extending supplemental guide rods 74, each of which is telescopically related to guide rods 24 or 54 as appropriate.

Each of guide rod 24 and 54 is provided with a plurality of spaced openings 76 which extend vertically therethrough and supplemental guide rods 74 are provided with a plurality of like openings 78 therethrough registerable with openings 76, wherefore a locking device 80 such as a U-bolt may be inserted into registered openings 76 and 78 to preclude movement of the extensions relative to the clamping devices.

The extensions may be adjusted to a plurality of positions by the simple expedient of removing the U-bolts and realigning certain other of openings 76 and 78.

Of course, when longer rolls are being cut, the extensions may be omitted entirely.

The clamping devices are disposed on opposite sides of the roll and the clamping plates are brought to bear tightly against the adjacent side faces of the roll in clamping manner to hold the roll in position more or less centrally of and relative to the structure for the slitting operation.

The clamping plates are so located as to embrace the roll and immobilize it, holding the roll at points below the central axis thereof so as not to interfere with the slitting action, it being understood that the roll is preferentially positioned centrally of and beneath the knife so that the knife initiates its cutting action at substantially the "top" of the roll and continues to cut radially therethrough.

A horizontally-disposed reciprocable mounting bar 82 is supported by and disposed between the stands, the opposite ends thereof being receivable through pairs of spaced, parallel, vertically-extending inner and outer guideways 84 and 86 respectively fixed to the inner and outer faces of each of stands 10.

The mounting bar is movable vertically relative to the stands within limits as determined by the vertical dimensions of the guideways, the opposite ends of the mounting bar being carried by wheeled inner and outer trolley assemblies 88 and 90 respectively which roll along and relative to the respective guideways.

One end of the mounting bar is operatively connected to means for effecting its vertical movement, and the opposite

end of the mounting bar is operatively connected to means for effecting its horizontal reciprocating movement.

The means for effecting its vertical movement includes an air or pneumatic cylinder 92, the piston rod 94 of which is connected to a bracket 96 fixed to one of the outer trolley assemblies 90, bracket 96 having an arm 98 depending therefrom and fixed at its lower end to the adjacent end of the mounting bar, arm 98 being pivoted at its upper end at 100 to the bracket, wherefore the arm may swing relative to the bracket as the mounting bar is horizontally-reciprocated.

The cylinder has a combination inlet and outlet at its upper end and a similar connection at its lower end. These connections all run to a single conventional four way valve which will supply fluid pressure, preferably compressed air, alternately to opposite ends of the cylinders.

A cable 102 is secured to each outer trolley assembly 90 and is entrained around a pair of lower pulleys 104 journaled relative to each stand 10 and around pairs of upper pulleys 106 journaled relative to brace beam 14 at opposite ends thereof so that vertical movement of one end of the mounting bar effects concomitant movement of the opposite end thereof thereby to effectuate a raising or lowering of the mounting bar relative to the stands and relative also to a roll positioned therebetween.

A horizontally-disposed cutting knife 108 is fixed to and depends downwardly from the mounting bar so as to be freely reciprocable horizontally with the mounting bar upon actuation.

An oscillatory means 110, of any well known type, drives the mounting bar and knife in oscillatory motion along its longitudinal axis, same being driven by a motor 112, the motor and oscillatory means being mounted upon a suitable bracket 114 secured to one of the outer trolley assemblies 90, the motor being connected to the oscillatory means as by a chain or belt drive, not shown. The oscillating means may comprise a pneumatic or electrical oscillator of the type which will produce the desired oscillations in the amplitude range of say 1 inch only and in the frequency range of say 275 to 300 strokes per minute.

Operationally, a roll is suitably positioned centrally of stands 10 and is held secure relative thereto by the clamping devices.

The cylinder connected to the mounting bar is preferably such as to exert a dimensional force of approximately 20 pounds per square inch when released from fixed position with the cutting edge of knife 108 being brought to rest upon the uppermost peripheral surface of the roll.

The motor is thereupon energized to actuate oscillatory means 110 to bring about the reciprocation of mounting bar 82 and cutting knife 108.

The reciprocating motion of the cutting knife produces a severing action in that the knife edge thereof penetrates through successive layers of the paper of the roll until all layers of paper along the radius of the roll have been severed.

As a layer of paper is thus split, it exhibits a tendency to fall away from the knife on each side thereof due to the weight of the paper itself and to assume a horizontal position upon the floor or base supporting the roll.

Following the slitting of the roll along a radius, the knife may be raised upwardly from the core of the roll to the inoperative position indicated by the dash lines in FIG. 1, wherein the knife is contained within a guard 116 suspended from brace beam 14 as by hangers 118.

As the knife makes contact with the roll, the initial action is one of compression. The roll is flattened at top and bottom and is distended laterally. When the limit of compression is reached, the knife begins to cut through the consecutive layers of paper, reducing each convolution to an independent sheet. The combined profiles of the knife and its holder are such as to separate the severed edges of each convolution, which, due to the lateral distension of the roll are under tension. The result is that the severed convolutions promptly "flop" into the general plane of the frame. The knife, therefore is self-

clearing. This is an important feature since the knife may be called on to cut through as much as 60 inches of superimposed plies.

I claim:

1. A paper roll splitter for splitting a paper roll along and through a radius thereof comprising in combination: a frame in the form of a pair of spaced vertically-extending stands disposed as to each other for the disposition of the paper roll therebetween; a pair of telescoping clamping devices for holding the paper roll in fixed relationship to and between the stands of the frame; one of the clamping devices being power operated and including a vertically-extending clamping plate mounted on the inner ends of a pair of horizontally-extending guide rolls each telescopically related to a guide sleeve mounted on one of the stands of the frame with a power cylinder fixed relative to the stand and having a piston rod extendable through the stand and fixed to the clamping plate for motivating the clamping plate into embracing position with respect to a respective end of the paper roll; the other of the clamping devices being manually operated and including a vertically-extending clamping plate

mounted on the inner ends of a pair of horizontally-extending guide rods each slidably related to a guide sleeve mounted on the other of the stands of the frame for manually motivating the clamping plate into embracing position with respect to the other respective end of the paper roll;

a vertically extending guideway slot on the inboard face of each stand of the frame; a horizontally-disposed mounting bar extendable between and receivable through the respective guideway slots of the stands of the frame for horizontal and vertical movements relative thereto; power cylinder drive means operatively connected to one end of the mounting bar for effecting the vertical movement thereof, motor driven reciprocating means operatively connected to the opposite end of the mounting bar for effecting the horizontal reciprocating movement thereof, and a horizontally-disposed cutting knife mounted on and depending downwardly from the mounting bar for reciprocation therewith.
